UNITED STATES PATENT OFFICE.

SKINNER A. COLLIER, OF PROVIDENCE, RHODE ISLAND.

COMBINATION SHADE AND CURTAIN BRACKET.

1,095,551.

Specification of Letters Patent.

Patented May 5, 1914.

Application filed February 5, 1913. Serial No. 746,276.

To all whom it may concern:

Be it known that I, SKINNER A. COLLIER, a citizen of the United States, residing at the city of Providence, in the county of Providence and State of Rhode Island, and whose address is 385 Pine street, in said city, have invented certain new and useful Improvements in Combination Shade and Curtain Brackets, of which the following is a 10 specification.

The object of my invention is to simplify the structure in the manufacture of brackets for application to window-casings, and to render a device of this character capable of 15 supporting a shade-roller, a portière-pole, and a curtain-rod.

A further object in view is to provide a combined shade and curtain fixture stamped out of two pieces of metal, one fixed member constructed so as to avoid disfiguration by nail holes in the front face of a window-casing, and a removable member designed to support a portière-pole and a curtain-rod and adapted to be disconnected from the 25 fixed member, when the latter is to support a shade-roller only.

My invention consists in the special details of construction, and combination of parts, as hereinafter described and claimed.

In the accompanying sheet of drawings, wherein like reference characters indicate like parts, Figure 1 is a vertical section of my improved device, as in position on a window-casing. Fig. 2 is a perspective view 30 of the fixed member of the device, showing an integral arm of said member designed to support a shade-roller. Fig. 3 is a similar view, showing the removable member adapted to be attached to the fixed member and 35 designed to support a portière-pole and a curtain-rod. Figs. 4, 5 and 6 represent a modified construction of my device, Fig. 4 being a plan view of the device; Fig. 5, a side elevation of the device, and, Fig. 6, a 40 means to permit the bracket to be positioned to accommodate different lengths of curtain-supporting means.

In carrying out my invention I construct my improved bracket wholly from sheet 45 metal, which is cut, upset and punched, by means of a suitable power press, to form the structural parts in a device of this character.

My improved device consists essentially of

two parts, namely, a fixed bracket member 55 —a—, and a removable member —b—.

The bracket member has a flat upright base portion —a— adapted to rest against a window-casing, as —c—, and a horizontal portion —a¹— extends rearwardly from the 60 upper part of the base portion, and an arm —a²— projects from the lower part of one of the side edges of the base portion, and said arm is provided with an opening to receive the pintle of a shade-roller —d—. The 65 base portion —a— is provided with two vertically-arranged rectangular openings —a³— and —a⁴— through its central part, the upper opening —a³— to form a socket having opposed outwardly and inwardly-curved 70 lugs, as —a⁵, a⁶—, and the lower opening —a⁴— to form a bearing. The ledge portion —a¹— of the bracket member has a 75 downwardly bent part which is provided with fine saw-teeth, as at —a⁷—, to embed into the top edge of the window-casing in securing the bracket member in place. Instead of a toothed means —a⁸— the portion —a¹— may have a perforation to receive a nail —n— for securing the bracket member 80 —a— in a fixed position, in the manner shown in Figs. 1 and 2.

The member —b— is flat and has two branches —b¹— and —b²—. The free end of the branch —b¹— has an enlarged head 85 to freely enter within the socket —a³— of the fixed member —a—, and the inner edges of the head are curved, as at —b³, b⁴—, to fit upon the rear faces of the lugs —a⁵— of the socket, and the free end of the other 90 branch —b²— has a narrow projection —b⁴— to rest within the bearing —a⁴— of the member —a—. The member —b— has a semi-circular opening to serve as a bearing, as —b⁵—, to support a portière-pole 95 —e—, and a vertically-arranged spur is formed at the outer part of said member —b—, as at —b⁶—, to receive the perforated end of a curtain-rod —f—. The member —b— is made longer than the arm —a²— of 100 the fixed member —a—, in order that the portières may hang free from contact with the curtain of the roller —d—. When the member —b— is attached to the member —a— the weight of the portières has a 105 tendency to hold the projection —b⁴— within its bearing —a⁴— while the lugs —b⁵— prevent displacement of the head of the

branch —*b*¹— of the member —*b*—. The member —*b*— being separable of the member —*a*— permits of ready disconnection from the fixed member, when the latter is to support a shade-roller only.

By my construction and arrangement of parts I provide a useful device for the purpose intended, is simple and cheap to manufacture, eliminates injury to the woodwork by nail holes in the front face of a window-casing, and at the same time a device to support three pieces—a shade-roller, a portière-pole, and a curtain-rod.

What I claim and desire to secure by Letters Patent, is:—

The herein-described combined shade and curtain fixture stamped out of two pieces of metal and comprising a member having a flat upright base portion, said base portion having two central vertically-arranged openings, the upper opening to form a socket having opposed outwardly and inwardly-curved lugs, and the lower opening to form a bearing, a horizontal portion ex-

tending rearwardly from the base portion 25 and adapted to be secured to the top edge of a window-casing, said base portion having an arm projecting from the lower part of one of its side edges and having an opening to receive a pintle of a shade-roller, and a 30 flat removable member having branches, the free end of one branch having an enlarged head to freely enter the socket and the inner edges of the head curved to fit upon the rear faces of the lugs, and the free end of 35 the other branch having a projection to rest within the bearing, said removable member having a semi-circular bearing to support a portière-pole, and a vertically-arranged spur formed at the outer part of the said 40 last mentioned member to receive the perforated end of a curtain-rod.

In testimony whereof I affix my signature in presence of two witnesses.

SKINNER A. COLLIER.
